CENTRIFUGAL GOVERNOR FOR INTERNAL
COMBUSTION ENGINES

Max Hurst, Stuttgart, Germany, assignor to Robert Bosch Gesellschaft mit beschränkter Haftung, Stuttgart, Germany

Application May 2, 1938, Serial No. 205,614
In Germany May 11, 1937

7 Claims. (Cl. 264—2)

The present invention relates to centrifugal governors which, driven directly or indirectly, are suitable for governing the fuel supply of injection internal combustion engines.

5 Since the adjusting forces of known governors, which are utilized to govern engine requirements, rise in square ratio with the engine speed, there occurs with the known centrifugal governors the drawback that the centrifugal weights, which are 10 comparatively heavily proportioned for the purpose of satisfactory "no load" governing, develop very great forces in the working speed range, which lies substantially above the no load speed, or again at the maximum speed. These forces 15 must be balanced by springs, which are to be disposed within the governor, and of which the distinguishing values such as preliminary tension, or stiffness, must be so chosen that even in the lower working speed range the admissible degree 20 of non-uniformity is not exceeded. Accordingly, in the known centrifugal governors, the greatest possible ratio between the highest and the lowest or no load speed is substantially of the value 5:1.

It is, however, desirable, especially in internal 25 combustion engines, to increase the maximum speed substantially while maintaining the hitherto usual no load speeds. For the aforesaid reason, the centrifugal governors hitherto usually adopted cannot fulfil this need, even if there 30 are used as a governor loading several sets of springs, which become operative successively, and have graded preliminary tension and stiffness, or if according to another known proposal, a part of the centrifugal mass is trapped after a predetermined stroke by stops fitted to the governor 35 shaft and, in the range of the higher speed, only the remaining part of the originally operative mass is used for governing. As a matter of fact, in both cases the masses which revolve with the 40 governor shaft are very large in the upper speed range and necessitate a correspondingly strong construction of the whole governor.

By the present invention, the above recited difficulties are overcome and thus is made possible 45 an increase in the value between the highest and the lowest ratios to substantially 10:1 or even to values considerably above this figure.

According to the present invention, a transmission gear, having two drives, each of different 50 ratio, which are automatically changed or shifted from one to the other with changes in speed of the driving shaft, is interposed between a governor shaft, about which the centrifugal weights revolve, and the driving shaft of the governor. 55 At no load and lower speeds of the driving shaft, the governor shaft is preferably connected to the driving shaft by means of a centrifugal clutch and one of the two drives (high gear) of the transmission gear. The centrifugal clutch releases this connection when the driving shaft

reaches a speed above no load speed, whereon the driving shaft drives the governor shaft through a free wheel clutch and the other drive (low gear) of the transmission gear.

The invention is more particularly described 5 with reference to the accompanying drawing, which illustrates one form of construction of the invention by way of example and in which:

Figure 1 is a longitudinal section through a 10 centrifugal governor, and

Figure 2 is a vertical middle section through a 15 part of the governor shown in Figure 1, and on the line 2—2 thereof.

In the drawing a sleeve 15 is driven through a 20 pair of toothed wheels 11, 12 from a shaft 10, which drives an injection pump (not shown), whilst through a further pair of toothed wheels 13 and 14, a bush 16, which is rotatably mounted on the sleeve, is driven at a greater speed. The sleeve 15 is rotatably mounted on a shaft 20 25 journaled in ball bearings 17 and 18 on the governor casing 9. Into the shaft 20 are radially inserted two guide spindles 21 for two centrifugal weights 23, which are loaded by springs 22, and which engage by means of two bell crank levers 24 with an adjusting bolt 25 which is mounted in 30 a bore in the shaft 20 so as to be longitudinally displaceable therein. The bolt 25 carries a collar 26, in which is mounted a sliding ring 27 which engages with one arm of a lever 29, pivotally mounted for rotation about a spindle 28. The other arm of the lever 29 is connected by a 35 link rod 31 with a governing member 30 of the injection pump (not shown). The spindle 28 is connected to an operating lever 32, which can be 40 rocked about a stud 33, by means of an operating member (not shown) located outside the casing 9, for the purpose of adjusting the speed required to be maintained by the governor.

A shallow cylindrical drum 34 is connected 45 with the shaft 20, and is open towards the driving side of the governor to accommodate a free wheel clutch, which is in engagement with the sleeve 15, and which consists of two rollers 35 and a free wheel core 36, which engages two dogs 45 or entraining claws 19, fitted to the sleeve 15. The outer circumference of the drum 34 is engaged by a plurality of clutch members or cheeks 37 which are loaded by springs 38. Abutments 50 39 for the outer ends of these springs are supported on the inner rim of a bowl shaped part 40, which is rigidly connected or integral with the bush 16 and which with its inwardly directed rim part 41 extends partly over the coupling 55 cheeks and holds them safely without the use of additional securing elements in the position shown in Figure 1. As will be seen from Figure 2, filling elements 42 are further placed between the coupling cheeks 37, said elements serving 60

for guiding the cheeks and being preferably cut with the latter from an annular disc.

The governor operates in the following manner:

- 5 At low speeds of the engine consistent with no load, the coupling cheeks 37 are pressed against the outer circumference of the drum 34 by the springs 38, and the shaft 20 is thus driven by the coupling bowl 40 which is connected with the
- 10 relatively rapidly rotating bush 16. Under these conditions the rollers 35 cannot come into engagement with the inner wall of the drum 34 and the sleeve 15, which is revolving relatively slower, consequently runs with no load.
- 15 During this operation, the centrifugal weights, which are driven with a comparatively large transmission gear or ratio, exercise sufficient adjusting forces, even when the driving shaft 10 is revolving at low speeds, to be able to govern
- 20 with certainty, the no load amount of fuel delivered. If the speed is increased, then the coupling members 37 under the influence of centrifugal force, become released from engagement with the circumference of the drum 34 and move
- 25 outwardly against the action of the springs 38 to contact with the inner peripheral face of the coupling bowl 40. The shaft 20, which is now uncoupled from the bush 16, is thus driven by the relatively slowly moving sleeve 15, since the
- 30 rollers 35 are pressed firmly against the inner wall of the drum 34 by the guiding cam faces of the free wheel core 36.

The transmission ratios should be so devised by means of the toothed wheels 11, 12, 13 and 35 14 that the centrifugal weights 23 of the governor are still driven by the more slowly rotating sleeve 15 after the centrifugal clutch 31, 40 has been disconnected, at a speed which is sufficient to prevent the centrifugal weights 23 dropping back against the shaft 20. Above that speed of 40 the driving shaft 10 at which the centrifugal clutch is disconnected, i. e. above the no load speed, there begins the working speed range, within which the governor is set by means of 45 the operating lever 32, preferably with the use of the features characterised in the application of Hurst et al. Serial No. 39,080 filed September 3, 1935, now Patent No. 2,117,248, to any desired speed, which can be maintained automatically by the governor within the admissible degree of non-uniformity. If the drive which is revolving at a fairly high speed, which in the illustrated construction is represented by the bush 16 and the coupling bowl 40, is not already 50 disconnected in the range of the no load speed by means of the centrifugal clutch, but is only disconnected after a lower limit, which lies within the working speeds, has been exceeded, then the governor member 30 can be set to any desired speeds both in the lower and in the upper 55 working speed range by rocking the operating lever 32.

I declare that what I claim is:

- 65 1. A centrifugal governor suitable for governing the fuel supply of injection internal combustion engines, comprising a driving shaft, a governor shaft, centrifugal masses revolving with said governor shaft, an operable connection between said centrifugal masses and the means to be controlled thereby for displacement of said means in accordance with the position of said masses relative to said shaft, a transmission gear having two drives, each of a different ratio, between said shafts, and means driven by, and responsive to the speed of, said driving shaft for

changing from one driving ratio to the other of said transmission gear.

2. A centrifugal governor suitable for governing the fuel supply of injection internal combustion engines, comprising a driving shaft, a governor shaft, centrifugal masses revolving with said governor shaft, an operable connection between said centrifugal masses and the means to be controlled thereby for displacement of said means in accordance with the positions of said masses relative to said shaft, a variable transmission gear having two drives, each of a different ratio, between said shafts, a centrifugal clutch for releasing said governor shaft from operative connection with said driving shaft at a predetermined speed of said driving shaft and a free wheel clutch interconnecting said transmission gear with said governor shaft on operation of said centrifugal clutch.

3. A centrifugal governor suitable for governing the fuel supply of injection internal combustion engines, comprising a driving shaft, a governor shaft, centrifugal masses revolving with said governor shaft, an operable connection between said centrifugal masses and the means to be controlled thereby for displacement of said means in accordance with the position of said masses relative to said shaft, a transmission gear having relatively fast and slow elements providing two drives, each of a different ratio, between said shafts, a centrifugal clutch, responsive to the speed of said driving shaft, associated with the faster element of said transmission gear, and a free wheel clutch associated with the slower element of said transmission gear, said free wheel clutch operating only when said centrifugal clutch cuts said faster element out of said transmission gear.

4. A centrifugal governor as claimed in claim 3 in which the centrifugal clutch includes a hollow cylindrical part secured to said governor shaft and centrifugal clutch members adapted for engagement with the outer circumference of said cylindrical part, and said free wheel clutch includes clutch members adapted for engagement with the inner circumference of said part.

5. A centrifugal governor as claimed in claim 3, including a sleeve on said governor shaft and connected to said free wheel clutch, and in which the relatively faster element comprises a bush member mounted on said sleeve, which sleeve is coupled with said governor shaft through said centrifugal clutch.

6. A centrifugal governor as claimed in claim 3 and wherein the centrifugal clutch comprises a bowl shaped element having an inwardly directed rim part, coupling cheeks located in the hollow space determined by said rim part, springs resisting the outward displacement of said coupling cheeks against the periphery of said bowl, and filling elements within said bowl part serving to guide said cheeks in their radial displacement.

7. A centrifugal governor as claimed in claim 3 and wherein the centrifugal clutch comprises a bowl shaped element having an inwardly directed rim part, coupling cheeks located in the hollow space determined by said rim part, springs resisting the outward displacement of said coupling cheeks against the periphery of said bowl, and filling elements within said bowl part serving to guide said cheeks in their radial displacement, said coupling cheeks and said filling elements being cut from an annular disc.

MAX HURST. 75
